UNITED STATES PATENT OFFICE.

SIMON A. HUNTER, OF GRIFFIN, SASKATCHEWAN, CANADA.

TOOL-SHARPENER.

1,182,274.

Specification of Letters Patent.

Patented May 9, 1916.

Application filed May 26, 1915. Serial No. 30,586.

To all whom it may concern:

Be it known that I, SIMON A. HUNTER, a citizen of the United States, residing at Griffin, in the Province of Saskatchewan and Dominion of Canada, have invented certain new and useful Improvements in Tool-Sharpener, of which the following is a specification, reference being had to the accompanying drawings.

10 My invention relates broadly to new and useful improvements in tool sharpeners and has more particular reference to an improved device which is designed especially for use in sharpening disks of harrows.

15 One of the primary objects of the invention is to provide a sharpener which comprises a supporting frame, wherein the axle carrying the harrow disks may be journaled, and a sharpening tool which is mounted for longitudinal movement through the frame whereby it may be positioned for engagement with any one of the harrow disks arranged therein.

20 Another object is to mount the tool in such manner that it may be oscillated to compensate for laterally protruding portions of the disks being sharpened, should the disk be accompanied by such laterally displaced portions as a result of contact with rock or similar foreign articles when in use.

25 Another and important object of the invention is to provide a disk sharpening tool having a cutting or sharpening element which is mounted for lateral and radial adjustment with respect to the disk to be sharpened and is accompanied by a swingingly mounted roller which is yieldably held against the opposite side of the disk being sharpened and serves to hold the cutting element in active engagement therewith.

30 A further object of the invention is the provision of a disk sharpening tool in which the sharpening element and the roller by which it is held in engagement with the disk, are removably mounted and are adapted to be reversed as regards their relation to each other, whereby either side of a disk may be operated upon by the sharpening element, without requiring that either the 35 disk or tool be shifted.

35 Another object is to provide a holding roller which may be either rigidly or yieldably maintained in engagement with the disk to be sharpened on the side thereof opposed to the side being operated upon by the sharpening element.

Another object of equal importance with the foregoing is to construct a disk sharpening machine which is constructed with such regard to proportion, number and arrangement of parts that it may be cheaply manufactured, will be durable and efficient in service and may be easily operated.

40 The above, and other incidental objects of a similar nature, which will be hereinafter more specifically treated are accomplished by such means as are illustrated in the accompanying drawings, described in the following specification, and then more particularly pointed out in the claims which 45 are appended hereto and form part of this application.

45 With reference to the drawings, wherein there has been illustrated the preferred embodiment of this invention, as it is reduced to practice, and throughout the several views of which similar reference numerals designate corresponding parts, Figure 1 is a front elevation of the sharpening machine, a portion of the supporting structure being 50 broken away; Fig. 2 is a top plan view; Fig. 3 is a detail view in side elevation of the sharpening tool; Fig. 4 is a detail view of the modified form of holding rod for the roller arm; Fig. 5 is a detail longitudinal 55 section taken in a vertical plane through the rear portion of the tool, disclosing particularly the manner in which the head screw is attached to the head bar; Fig. 6 is a detail view looking at the face of the guide 60 block and showing this member in position against one of the track members, a portion of the guide block and body block of the tool being shown in section; Fig. 7 is a detail perspective view of the head bar; Fig. 65 75 8 is a detail view of the rear end of the roller holding arm; and Fig. 9 is a detail view in longitudinal section of the bearing employed in connection with one end of the 80 shaft or axle upon which the disks to be 85 sharpened are supported.

90 As best disclosed as an operative entirety in Fig. 1 of the accompanying drawings, the apparatus consists broadly in a supporting frame 10, wherein the disks to be sharpened indicated at 11 are supported and a sharpening device generally designated by the letter A, which is mounted for longitudinal adjustment within the frame.

95 The supporting frame includes four 110 corner legs or posts 12 connected by transverse beams 13, diagonal braces 14 and the

longitudinal beams 15, which latter members are preferably secured to the lower portions of the posts. Between the upper ends of the two front posts, extend, as best shown in Fig. 2, a pair of parallel I beams 16 and 17, while at the rear of the frame and between the upper ends of the two rear posts, there is mounted a single I beam 18 which extends in parallel relation to the beams 16 and 17. These I beams 16, 17 and 18 constitute tracks, the use of which will hereinafter become apparent. Spaced parallel bars 19 and 20 are terminally secured upon the I beams at one end of the supporting frame, as in Fig. 2. These bars are equipped with suitable bearings, which receive a stub axle 21, whereon the drive wheel B is keyed. This drive wheel meshes with a pinion C, the shaft D of which is accompanied by a belt wheel E. A belt F may be employed in connecting the belt wheel to an engine or motor or other suitable power source. The inner end of the stub axle extends beyond the bar 20 and carries a socket 22 wherein is inserted the terminal of the shaft or axle 23 which carries the disks 11. A set screw 24 is provided for the socket to secure the shaft 23 against rotation therein. This shaft 23 is the shaft which carries the disks 11, when these members are supported within the harrow frame and is in practice removed from the harrow and mounted in the supporting frame above described, when the disks are to be sharpened.

In supporting the shaft 23, I employ a pair of transverse beams 24^a and 25. The beam 24^a is mounted upon the I beams adjacent to the bar 20 and has a suitable bearing 39^a for the shaft 23. The beam 25 is mounted for movement longitudinally upon the I beam in order that it may be positioned at different points to accommodate disk shafts of varying length. The bearing 39 carried by the beam 25 is illustrated in detail in Fig. 9, to which figure reference will now be had. The bearing is provided at its inner end with an inwardly directed annular lip 41 which is triangular in cross section and, therefore, engages only a small area of the shaft so that the friction between the shaft 23 and the bearing is reduced to a minimum. A plug 50 having a longitudinally threaded bore is threaded into the outer end of the bearing. Through this plug is threaded the screw 54, the inner end of which carries a block which, as shown in Fig. 9, may be adjusted to bear lightly against the pointed end of the shaft 23. U clamps 67 may, as shown in Figs. 1 and 2, be employed to secure the beam 25 in adjusted position upon the beams 17 and 18 and, as herein disclosed, the clamps 67 have their extremities overlapping the upper surface of the transverse beam 25 and a flange of each of the beams 17 and 18 and the lower extremities of the

clamps are provided with the binding screws 68 coacting with the flanges of the beams 17 and 18 in order to effectively maintain the clamps in applied position yet permitting a ready and convenient release of the 70 clamps.

From the foregoing description, it will be readily observed that the disk may be rotatably supported within the frame and driven by means of the wheel E. 75

The sharpening device heretofore designated as an entirety by the letter A, is mounted for longitudinal adjustment upon the pair of track rails 16 and 17 and is secured in adjusted position by a means to be hereinafter described. The sharpening tool includes a rectangular body block 26, a slideable head bar 27, in which the sharpening element 28 is mounted, a swingingly mounted arm 29 in which the holding roller 85 30 is journaled, a setting screw 31, by means of which the roller is adjusted, and a head screw 32 which is employed in adjusting the head bar. 80

The body block 26 is provided in its upper face with a longitudinally extending groove or channel 33, through which the head bar is adapted to slide. The rear end of the body block is provided with a vertically extending plate 34, to the rear face of which is bolted a screw plate 35, which carries a nut 36 to receive the head screw 32. 90

The head bar 27, which as best shown in detail in Fig. 7, is in length approximately equal to the length of the body block and is provided at its forward end with a socket 37 which receives the sharpening element 28. The sharpening element 28 comprises an elongated member possessing the requisite grinding qualifications and is disposed through an opening formed through the inner end of the head bar 27 and said sharpening element 28 is of a length to extend beyond the opposite sides of the bar 27. The sharpening element 28 is maintained in applied position through the medium of the clamping member 38 which may be as desired but preferably a threaded shank provided at its outer end with a head whereby said shank may be properly rotated. At the forward end of the head block and on opposite sides thereof, are formed the laterally extending apertured ears 40. These ears are adapted for insertion through the slot 42 formed in the roller carrying arm 29 in the manner best shown in Fig. 3. A pivot pin 43 passes through this arm and the ears. The forward end of the roller carrying arm is bent to form a substantially U-shaped yoke 44, wherein the roller heretofore designated by the numeral 30 is journaled upon an axle 45. 100

The rear end of the roller arm 29 is provided with a socket 46, wherein is pivotally mounted, by means of trunnions 47, a screw 105

block 48 having a threaded opening, through which the setting screw 31 is passed. The outer end of this setting screw is provided with a removable handle 48^a and the 5 inner end of this screw carries a head block 49 which is adapted to bear against the bracket plate 55 of the head bar, as shown in Fig. 2. A pair of these bracket plates extend from opposite sides of the head bar, adjacent to the rear end thereof. It will be 10 seen that the screw rod 31 is swingingly mounted with respect to the roller arm 29 and that it may be adjusted to swing the holding roller to the proper position for 15 maintaining the sharpening element in engagement with the face of the disk being operated upon. The screw rod above described is employed when it is desired to maintain the roller in relatively fixed relation to the members 28.

When it is desired that the roller be yieldably held against the face of the disk, as when this member is accompanied by numerous indentations and projections resulting from rocks and the like, I employ a 25 modified form of adjusting rod shown in detail in Fig. 4. This adjusting rod is provided at one end with a head block 51 and is threaded at its other end to receive a 30 wing nut 52. A helical spring 53 is wound about the rod and is disposed to bear at its inner end against the head block 51 and at its other end against the screw block 48. It will be seen that this modified form of 35 rod may be employed in yieldably holding the roller and consequently the sharpening members 28 against the face of the disk.

The lower face of the head bar is provided adjacent to the rear terminal of this 40 member with a relatively large recess 56. Leading from this recess is a horizontal opening 57, through which the head screw 32 passes. The forward end of this head screw is disposed within the recess 56 and is 45 held against withdrawal therefrom by a block 59 and a pin 60.

From as much of the description as has now been given, it will be apparent that the cutting element 28 may be radially adjusted 50 with respect to the disk to be operated upon by means of the head screw and that the roller may be either yieldably or rigidly engaged against the opposite face of the disk for maintaining the element 28 in engagement therewith.

As a means for attaching the body block to the track rails 16 and 17, I employ a guide block 62 and a substantially L-shaped attaching bracket 63. The block 62 is adapted 60 to be disposed between the rails and is provided on opposite faces with a pair of parallel grooves which receive the flanges of the rails. The block is keyed by a pin 64 on an axle 65, which is journaled at its upper end in the body block 26 and at its lower

terminal in a horizontal arm of the bracket 63. The lower end of this axle is threaded to receive a clamping handle 66, by means of which the horizontal arm of the bracket may be forced against the tracks 16 and 17 70 and clamped against turning movement. The tightening of the member 66 also serves to clamp the block 62 against movement. Thus the body block 26 of the tool is held against rotative and longitudinal movement 75 since its two points of support, the axle 65 and the L bracket, are held in fixed position. When the clamping handle is loosened, the body block is, of course, adapted to swing about the axle 65 so that the cutting member 28 and holding roller may swing to accommodate indentations or protrusions in the disk which is being cut.

Having thus disclosed the actual construction and arrangement of the several parts of the invention, it now remains to describe briefly the manner in which the tool is employed when in use and to enumerate the principal advantages which result from the particular construction embodied in the accompanying drawings. When a number of disks are to be sharpened, they are mounted in the frame and the sharpening device is then positioned opposite the first disk to be sharpened. If the disk has been considerably damaged and its periphery is wavering, so that the element or member 28 would unevenly cut into the face of the disk, were it (the element or member 28) maintained in fixed position, the clamping handle is 90 loosened so that the body block may be swung about the axle 65, as an axis. When the body block is thus free, it is obvious that irregularities in the face of the disk will be compensated for, since the element 95 or member 28 and the holding roller will swing laterally as the distorted portions of the disk pass between them. The sharpening element or member 28 may be brought into engagement with the proper portions 100 of disks of different diameters, without requiring that the position of the disks within the frame be varied or the track rails moved, it being only necessary to manipulate the head screw 32. After the first disk has been 105 cut, the guide block may be shifted longitudinally on the rails to dispose the sharpening device in position for engagement with the next disk.

Of course, if desired, the sharpening device may be clamped in fixed position upon the track, even through the disk to be sharpened has been somewhat distorted in service.

In some instances, it is desirable to true up the disks and in such cases, the sharpening device should be fixed.

Principal among the advantages offered by the particular construction of the sharpening device of my present invention, are the radial adjustability of the sharpening 120

element 28 with respect to the disk being cut; the fact that the body block may be either swingingly or fixedly secured; the fact that the roller carrying arm may be either held in relatively fixed position or may be yieldably held to maintain the roller in engagement with the disk; the fact that the sharpening element 28 and the holding roller may be reversed in their relation to each other for permitting the use of the sharpening device in facing either side of a disk, and the fact that the roller being semi-ovoidal in shape, may accommodate itself to the face of the disk, regardless of the particular angle which the roller carrying arm bears to the body block.

In reduction to practice, it has been found that the form of this invention illustrated in the drawings and referred to in the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claims.

What is claimed is:—

1. A disk sharpening machine including a supporting frame wherein disks to be sharpened may be rotatably supported, a pair of parallel tracks extending longitudinally through the frame in parallel relation to the axis of rotation of the disks to be sharpened, a guide block supported between the tracks and movable longitudinally

through the frame, a sharpening carrier rotatably mounted on the guide block, a substantially L-shaped bracket secured to the carrier and having its horizontal arm disposed beneath the guide block for supporting the same, and means engageable with the horizontal arm of the bracket for clamping the carrier upon the guide block whereby the carrier may be held against rotation thereon.

2. A disk sharpener including a body block, a head block slidable longitudinally therein, a head screw detachably connected to the body block, a screw plate formed integrally with the body block and receiving the head screw, a socket formed at the forward end of the head block, a sharpening element removably mounted in the socket, and means carried by the head block and engageable against a disk to be sharpened for yieldably maintaining the sharpening element in engagement therewith.

3. A disk sharpening machine including a supporting frame wherein a disk to be sharpened may be rotatably supported, a guide block movably mounted upon the frame, a sharpening carrier rotatably mounted on the block, a bracket carried by the carrier and extending beneath the guide block for supporting the same, and means coacting with the bracket for clamping the carrier upon the guide block for holding the carrier against rotation.

In testimony whereof I hereunto affix my signature in the presence of two witnesses.

SIMON A. HUNTER.
